United States Patent Office

Des. 185,219
Patented May 19, 1959

185,219

FAMILY ALTAR OR SIMILAR ARTICLE

Boles Liubauskas, Du Bois, Pa.

Application February 28, 1958, Serial No. 49,846

Term of patent 14 years

(Cl. D29—23)

I claim:

The ornamental design for a family altar or similar article, as shown.
